UNITED STATES PATENT OFFICE

ALMARIN B. PAUL, OF SAN FRANCISCO, CALIFORNIA.

IMPROVEMENT IN TRAPS FOR AMALGAMATING-PANS AND SETTLERS.

Specification forming part of Letters Patent No. 173,492, dated February 15, 1876; application filed December 18, 1875.

To all whom it may concern:

Be it known that I, ALMARIN B. PAUL, of San Francisco, San Francisco county, State of California, have invented a Trap for Amalgamating-Pans and Settlers; and I do hereby declare the following description and accompanying drawings are sufficient to enable any person skilled in the art or science to which it most nearly appertains to make and use my said invention and improvements without further invention or experiment.

My invention relates to a device the object of which is to obviate the necessity of stopping the machinery in order to clean up amalgamating-pans and settlers.

In order to describe my mercury and amalgam discharger, so that others will be able to understand its construction and operation, reference is had to the accompanying drawings forming a part of this specification, in which—

Figure 1 is a view of the mercury and amalgam discharger, showing the pan attachment. Fig. 2 is the dial.

Through the bottom of the amalgamating-pan or other vessel A I make a hole at some point near its outer rim or periphery, into which I screw a short tube, b, from the bottom up into the pan. In the lower end of this tube I screw another piece of tubing, c, to the lower end of which I attach a hollow globe or other suitable reservoir, D. This reservoir or receiver can be made in two parts, as shown, and united at the middle by flanges, so that the lower half of the globe can be removed when desired. A tube, e, projects downward from the bottom of the globe or reservoir D, which has a screw, f, turned into its open end, so as to serve as a plug for closing the hole. A small hole, g, is made diagonally through the lower end of the tube e, so that its upper end will communicate with the opening which is closed by the screw f at a point which will be below the end of the screw when it is turned up into the tube, but provides a vent or passage when the screw is partly turned out or withdrawn.

The globe D and tubes b and c will be kept constantly filled with mercury, and, as the amalgam accumulates in the amalgamating-pan or other vessel with which the tube b connects, it will descend through the tubes by its supe-

rior specific gravity to the lowest part of the globe or trap, from which it can be removed by withdrawing the set-screw f, so as to uncover the upper end of the diagonal vent-hole g, and allow the amalgam to pass out.

A tube, G, is connected with the upper portion of the globe, which is long enough to carry the discharge of quicksilver to the desired point. At the end of this tube G an elbow, h, is attached, so that it can be turned to any desired position about the end of the tube G, and another tube, i, is screwed or otherwise secured upon the upturned end of the elbow. This tube i is long enough to extend, say, two or three inches above the upper end of the tube b, which connects with the vessel A when it is in a perpendicular position. An elbow or curved spout, J, is then secured to the upper end of the tube i, for the purpose of giving direction to the mercury when flowing off. A dial or quadrant, K, is permanently attached to the outer end of the tube G, next to the elbow h. This dial or quadrant is graduated, as shown at Fig. 2.

The operation is as follows: Before charging the pan or other vessel with ore or water the tube i is placed in a vertical position, and mercury poured into the tube b until the reservoir and pipes are filled. The mercury will then stand in the pipe i on a level with the mercury in the globe or reservoir. The pans or other vessels are then filled with water up to the lowest point at which it is generally discharged during regular running. The elbow h is then turned upon the end of the tube G, so as to lower the upper end of the pipe i by turning it in a circle until the mercury shows itself ready to drop from the nozzle or curved spout J. This point is noted on the dial or indicator as the point at which all surplus mercury and amalgam can be drawn off. After the pan has run awhile, and amalgam has been deposited in the globe or trap, the mercury will rise in the tube i, when, by again lowering this tube, the height of the mercury can be ascertained by the drip, and a sufficient quantity of amalgam and quicksilver drawn off through the vent-hole g, as above described, until the proper level has again been attained.

This process of removing the accumulated

amalgam and surplus quicksilver can be accomplished at any time while the pans are working, without interfering with their operation in the least, or stopping the machinery.

It is desirable to give the vessel to the bottom of which the tube *b* is connected a slight inclination toward the point of discharge, say of one-eighth of one inch to the foot.

When running, the pipe *i* should remain in a vertical position, and the vessel can be kept filled as full as desired. When it is desired to run off mercury, lower the pipe or tube *i* gradually as the pressure lessens, for flow of mercury, and until it reaches the desired point, as indicated on the dial.

Where the device is to be used for metals lighter than mercury, as silver, the globe or trap *d* is dispensed with, and the tubing *c* and *G* are connected by a simple elbow. The remainder of the apparatus and process is the same as above described.

Valves or other plugs *s* and *s'* should be used to cut off the communication between

the trap and pan while drawing off the amalgam and quicksilver from the reservoir.

To wash the reservoir or trap out, so as to remove any clinging or lodged amalgam, throw in clean mercury, which will dislodge and carry it out.

Having thus described my invention, what I claim, and desire to secure by Letters Patent, is—

1. In combination with a trap or reservoir, for collecting amalgam from pans, and settlers, I claim the pipe *G*; swiveling-elbow *h*, and tube *i*, for the purpose specified.

2. The fixed dial or indicator *K*, in combination with the swiveling-tube *i*, tubes *G* and *c*, and trap *D*, substantially as and for the purpose above described.

In witness whereof I hereunto set my hand.

ALMARIN B. PAUL.
